(57) **CLAIM**

The ornamental design for a water jet massage apparatus, as shown and described.

DESCRIPTION

FIG. 1 is a perspective view of the water jet massage apparatus shown in the closed position of my new design; FIG. 2 is a front elevation of the water jet massage apparatus of FIG. 1;

FIG. 3 is a left side elevation view of the water jet massage apparatus of FIG. 1, the right side being a mirror image thereof;

FIG. 4 is a left side elevation view of the water jet massage apparatus shown in the open position;

FIG. 5 is a rear elevation view of the water jet massage apparatus of FIG. 1; and,

FIG. 6 is a top plan view of the water jet massage apparatus of FIG. 1.

The broken lines are for illustrative purposes only and form no part of the claimed design.
